A. STREETER.

Corn Planter.

No. 35,280.

Patented May 13, 1862.

UNITED STATES PATENT OFFICE.

ALONZO STREETER, OF ADRIAN, ASSIGNOR TO HIMSELF, AND THOMAS FARRAR AND AMZI CHASE, OF WELLSVILLE, MICHIGAN.

IMPROVEMENT IN CORN-PLANTERS.

Specification forming part of Letters Patent No. 35,280, dated May 13, 1862.

To all whom it may concern:

Be it known that I, ALONZO STREETER, of the city of Adrian, county of Lenawee, and State of Michigan, have invented a new and useful Improvement in Corn-Planters; and I do hereby declare that the following is a full and exact description thereof, reference being had to the accompanying drawings, and to the letters of reference marked thereon.

The nature of my invention consists in the arrangement of certain parts of mechanism, whereby a machine is produced for planting two rows of corn at once by animal power.

Figure 1 of the accompanying drawings is a perspective view of my machine exhibiting its several parts—viz., main frame A, wheels B, hoppers D, their spouts E, seat F, lever G, rock-shafts H, connections I, lever M, lever L, brake N, connections O, guide-bar P, guides S, windlass T, crank U, revolving cutters R, shoes Q, and tongue Z.

Fig. 2 exhibits my machine from a point of sight directly above the same, with its hoppers D removed therefrom, showing the parts that cannot be seen in Fig. 1—viz., main shaft C, rope V, sheave W, cams seen at the numerals 1, elbow-levers 2, levers 5, connections 6, pivots 7, pivot 10, dotted lines 9, dotted lines 45, and pivot 31.

Fig. 3 shows one of the hoppers D removed from the machine, with its side open, for the purpose of showing its internal parts, which I will describe as follows: its partition 12, spiral spring 13, its case 14, plunger 15, its lug 16, lug 27, cover 30, blocks 29, spout 25, valve-seat 24, valve 20, brush 40, and cap 39.

Fig. 4 shows the partition 12 removed from the hopper D, exhibiting its valve-seat 24, brush 40, spout 25, slot 26, cap 39, and blocks 29.

Fig. 5 exhibits the reversed side of partition 12, showing the lower end of spout 25 and slot 26.

Fig. 6 shows the partition 12, with the valve 20 attached thereto covering the slot 26, through which the valve-stem 21 passes, exhibiting also the block 29, spout 25, valve-seat 24, brush 40, cap 39, and the metallic case 14, that covers the spiral spring 13.

Fig. 11 shows an edge view of the plunger 15, with its lug 16, spiral spring 13, and lug 27, that attaches the spiral spring thereto.

Fig. 12 shows the side of the hopper D to which the spout E is attached, exhibiting the slot 17, through which the lug 16 plays.

Fig. 13 shows the plunger 15 removed from the spout E, exhibiting its angling slot 19, through which the valve-stem 21 plays.

Fig. 14 exhibits the lug 27 removed from the plunger 15, showing the hole in which the rod is fastened that attaches the spiral spring thereto.

Fig. 7 shows the valve 20 removed from the hopper, exhibiting its slide 22, set-screw 23, stem 21, and throat 37.

Fig. 8 shows the other side of the valve, with its throat 37 enlarged by means of set-screw 23.

Fig. 9 shows the lever 5 removed from the machine, exhibiting the manner in which the elbow-lever 2 is attached thereto.

Fig. 10 shows the cam 1, elbow-levers 2, and lug 16 removed from their respective places for the purpose of showing the manner in which the elbow-levers 2 act on the lug 19 by means of the cam 1.

Fig. 16 shows the valve-seat 24 with the valve-seat laid off, exhibiting its throat 38, cap 39, and brush 40.

Fig. 15 shows the valve-seat 24 and valve 20, with the valve thrown back, the throat 37 being out from under the brush ready to receive the corn from the hopper D.

Fig. 17 shows the valve-seat 24 and valve 20, with the valve thrown under the brush in the position that the valve is in when its throat 37 is over the throat 38 in the valve-seat 24.

Fig. 18 shows an end view of the hopper D, exhibiting its plunger 15, partition 12, blocks 29, valve 20, slide 22, throat 37, cap 39, brush 40, set-screw 23, and spiral spring 13 in their proper places.

Fig. 19 shows an end view of the hopper D, described in Fig. 18, with all its internal parts removed.

The hoppers D are four in number. All of them are constructed alike, after the manner above described, and they are attached to wheels B at the numerals 41, with their spouts E extending through the slot in the rims of the wheels at 42, as is clearly seen in Fig. 1, when the hoppers D are all adjusted ready for planting. The valve-stem 21 in Fig. 3 passes through the slot 28 in the partition 12 and into

the slot 19 in the plunger 15. The end of the set-screw 23 passes through the hole in the side of the hopper, as seen at the number 23, so that the operator can regulate the size of the throat 37 without opening the hopper or removing the valve. The object of the brake N is to lock the wheels when the machine is being turned around, and to enable the operator to have the spouts E strike the ground at any place he may desire. The object of the slide P and guides S is to enable the operator to drive the machine so that it may plant the rows of corn at equal distances apart. The object of the cutters R and shoes Q is to cut the sod and remove obstructions in advance of the wheels B as the machine is being drawn along.

When the operator wishes to draw the machine along without having it plant he throws the levers 5 into the position shown by the dotted lines 45 by means of lever L and connections 6, which allows the wheels B to revolve without having the lugs 16 strike the levers 2. Said connections are attached to lever L at equal distances from the pivot 7, on which it oscillates, so that one motion of the lever throws both levers 5 in or out, as the case may be.

I will describe the operation of my machine as follows: After the operator has filled the hoppers with corn he adjusts the throats 37 by means of set-screws 23. He then draws the machine to the place where he intends to commence planting; then throws the lever M forward, and as it oscillates on its pivots 10 it removes the brake N from the wheels B by means of the connections I; then raises the lever G until it catches in the notch in the top of the post K. That in turn allows the shoes Q and revolving cutters R to be pressed down on the ground by means of their connections O and spiral springs 4. He then throws the top of lever L to the right, that in turn throws levers 5 and 2 from the position of the dotted lines 45 by means of connections 6 to the proper place to have the lugs 16 and cam 1 strike the levers 2 as the wheels B revolve. Then as the machine is drawn along the cutters R split the sod or lumps, and the shoes Q follow and clear any obstructions in advance of the wheels B. As the wheels B revolve they give simultaneous movement to shaft C, cam 1, and hoppers D. Then as the wheels revolve the lugs 16 strike the elbow-levers 2, as seen in Fig. 10, the other end of lever 2, being struck simultaneously with cam 1, raises the plunger 15 in the spouts E by means of lug 16, that in turn throws the valve 20 from under the brush, as seen in Fig. 17, to the position seen in Fig. 15 by means of its stem 21 playing in the angular slot 19 in said plunger, said slot being seen in Fig. 13.

Then when the wheels B have revolved to the right position to have the spouts E forced in the ground by the weight of the machine the hoppers then stand in a vertical position, and the plungers are raised so that their lower ends are above the juncture of the spouts E and 25. Then as lugs 16 pass by the end of the lever 2 the combined force of gravitation and spiral spring 13 forces the plunger to the lower end of spout E. While the plunger is on its downward passage the slot 19 throws valve 20 to the position seen in Fig. 17 by means of its stem 21, which brings the throat 37, after having been filled with corn from the hopper, under the brush 40 and over the throat 38 in the valve-seat 24. The corn then is free to fall from thence into the spout 25 and enter spout E in advance of the plunger, and is driven into the ground by the force of the plunger as it strikes the ground. After the machine has been drawn across the field and the operator wishes to turn around preparatory to planting another row he presses lever G down until it catches in the lower notch in post K, that in turn raises the cutters R, shoes Q, and connections O by means of the connections I, which play in the slots in the ends of levers G. He then locks the wheels, as above described, and turns the machine around. He then turns the crank U, that in turn moves the slide P and guides S to the right or left, as the case may require, by means of the windlass T, rope V, and sheave W, when the guide S is thrown to one side, as seen in Fig. 1. The guide that is on the end of the slide being out hangs over the track previously made by the wheel, by which means the operator drives the machine so that the rows of corn are all at equal distances apart.

After thus describing my machine and invention, what I claim, and desire to secure by Letters Patent, is—

1. The combination and arrangement of hoppers D and wheels B, as above described, for the purposes described and set forth.

2. The combination of the post K, lever G, shaft H, connection I, spiral springs 4, connection O, shoes Q, and cutters R, for the purposes set forth and described.

3. The combination of the levers 5 with the elbow-levers 2, for the purposes above described.

4. The crank U, windlass T, rope V, and sheave W, in combination with slide P and guides S, for the purposes set forth and described.

ALONZO STREETER. [L. S.]

In presence of—

R. B. ROBBINS,
GEO. H. GRANT.
